GAS CONSUMING DEVICE

James S. Blackmore, Edgewood, Pa., assignor to
Automatic Gas-Steam Radiator Company,
Pittsburgh, Pa., a corporation of Pennsylvania

Application September 10, 1929
Serial No. 391,571

1 Claim. (Cl. 158—115)

My invention relates to gas consuming devices and more particularly to gas burners and pilot lights.

For safety in many gas burning devices it is desirable to have a pilot light which is fed by a substantially continuous supply of fuel disposed adjacent to a burner having a separate fuel line so that in case gas is accidentally turned on to the burner the gas will be lighted. Pilot lights are particularly useful where the supply of fuel to burners is controlled automatically, as by a thermostat. In such constructions the supply of gas to the burner is interrupted periodically to control the temperature of a medium being heated. When it is desired to again light the burner the supply line is opened and the burner is ignited by the pilot light, which is not extinguished with the main burner.

In such constructions difficulty has heretofore been experienced in maintaining the pilot light in proper spaced relation to the burner to insure automatic ignition of the latter. Workmen are liable to remove the pilot light and burner and fail to replace the pilot light. In some instances the pilot light is replaced, but in a faulty position. Most pilot lights heretofore used have burned with a yellow flame and not with the blue flame characteristic of a Bunsen burner.

Gas burners are generally placed in a combustion chamber located in the casing of a space heater, hot water heater, or the like. The burner comprises a plurality of small openings or jets connected to a duct for supplying gas. The several jets have been disposed inside the casing at a distance from an opening in the casing through which a match or burning taper is inserted for igniting the jets. Difficulty is often experienced in moving the lighted match or taper over the jets immediately upon inserting it through the opening in the casing. During the delay an appreciable quantity of gas escapes into the casing and when the jets are lighted there is likelihood of a puff or small explosion.

I provide a gas burner in which a small section of the burner is walled off to constitute a chamber to which the source of gas for the pilot light is connected. By having the pilot light made a part of the burner, danger of inserting the burner without a pilot light is eliminated. Also, danger of the pilot light and burner becoming relatively dislocated is prevented. By providing the chamber with air openings, the pilot light is made to operate as a Bunsen burner with a characteristic blue flame. The proximity of openings in the pilot light chamber to the jets in the main burn-

er insures the rapid propagation of a flame from the pilot light to the jets as soon as gas escapes from the jets.

To insure ease in lighting the burner by a taper or flame inserted into an opening in the burner housing, I provide an arm or prong terminating adjacent to the opening. Jets on the arm are provided which propagate a flame along the arm to the rest of the burner as soon as a flame ignites the jet nearest the opening. This construction eliminates the delay which has heretofore existed in bringing a flame inserted through such an opening into engagement with one of the burner jets, with the resultant liability of a puffing or small explosion.

The accompanying drawing illustrates a present preferred embodiment of the invention in which,

Figure 1 is a cross-sectional view in plan of a portion of a gas consuming device embodying my invention, and

Figure 2 is a transverse sectional view thereof taken along the section line II—II of Figure 1.

Referring to the drawing, a gas consuming device 2 is illustrated in the form of a radiator having a plurality of intermediate sections 3 and an end section 4. The intermediate sections 3 are of similar shape and have ribs or beads 5 along their edges engaging complementary beads on adjacent sections for forming a combustion chamber 6. The end section 4 is provided with an opening 7 that is closed by a plate 8. The end section 4 is provided with legs 9 for supporting the radiator. As is well understood in the art the radiator comprises several of the intermediate sections 3, an end section 4, and a complementary end section (not shown) at the other end of the radiator. The size of the radiator is controlled by the number of the intermediate sections 3. The sections 3 and 4 may be used to heat air or they may be provided above the combustion chamber with cross walls constituting retaining walls for a heating medium, such as water or the like.

The combustion chamber 6 houses a burner 10 having a central duct 12 from which arms or prongs 14 project laterally. The tops of the duct 12 and the arms 14 are slightly flattened to provide bases for jets 15, each of which supports a separate flame. The duct 12 extends through an opening 16 in the plate 8 and terminates in a connection 17 leading to a regulating or supply valve for the gaseous fuel.

To insure the proper lighting of the several jets 15 as soon as gas escapes therefrom, I separately

supply an arm 18 with gas to constitute a pilot light. A wall 19 is cast in the arm 18 to isolate a chamber 20 formed therein from the duct 12. A dependent hollow lug 21 is provided at the lower 5 surface of the arm 18 for the reception of a needle valve 22 which is connected to a gas line 24 controlled independently of the duct 12. Openings 25 are provided in the walls of the lug 21 to admit air above the valve 22 so that the fuel in the 10 chamber 20 is mixed with air. Escape openings 26 are provided at the sides of the arm 18 which 15 serve as burner jets. As the fuel in the chamber 20 is mixed with air, the flames from the opening 26 have the characteristic blue color of a Bunsen burner. The openings 26 are inclined laterally of the arm 18 so that the flames are projected outwardly toward the adjacent arms 14, thereby insuring a quick ignition of the neighboring jets 15. Where the pilot flame or flames project in a vertical 20 direction, it is necessary for gas from the neighboring jets to be moved into engagement with the pilot flame by convection currents, thereby causing a time delay in the lighting of the burners with a resultant liberation of raw gas. 25 When considerable quantities of such gas collect in the housing there is danger of an explosion when it becomes ignited.

By having the pilot light integral with the main burner, danger of the pilot light being left 30 out of the gas consuming device is eliminated and the proper position of the pilot light relative to the burner jets is maintained at all times.

For igniting the burner independently of the pilot light, I provide an opening 27 in the plate 8 35 through which a burning match or taper is inserted. In order to insure prompt lighting of the burner upon the insertion of such a flame, an arm 28 adjacent the opening 27 is curved to pro-

vide a jet 15 immediately in front of the opening 27. As soon as the flame is inserted in the opening 27 and the first jet 15 is ignited, the flame is propagated along the adjacent jets until the entire burner is ignited. The jets 15 are preferably 80 placed close enough together to prevent time delays in the transmittal of the flame.

The arm 18 is provided with a pair of the jets 15 to insure similar propagation of the flame along the burner when it is lighted from the pilot 85 light.

While I have shown and described my invention in connection with a gas-fired radiator, it is to be understood that certain other features thereof are not limited to use with radiators, but 90 may be used with other gas-fired devices, such as water heaters, boilers and the like. Also, the exact shape of the burner may be varied.

While I have shown and described the present preferred embodiment of the invention, it is to be understood that it may be otherwise embodied within the spirit of the invention and the scope 95 of the appended claim.

I claim:—

In a gas burner, a linearly extending duct having 100 a connection for a gas supply pipe, arms extending at right angles from said duct at spaced points therealong, nozzles in said arms, and a transverse wall extending entirely across one of said arms for isolating it from the duct, the other 105 arms communicating with said duct, and independent gas supply means for said isolated arm, whereby it constitutes a pilot burner, the nozzles of said last-mentioned arm being disposed to provide divergent flame jets for igniting gas issuing 110 from the nozzles of adjacent arms.
